WESTEL E. HAWKINS, OF WALLINGFORD, CONNECTICUT, ASSIGNOR TO
SIMPSON, HALL, MILLER & CO., OF SAME PLACE.

Letters Patent No. 74,221, dated February 11, 1868.

IMPROVEMENT IN BUTTER-DISHES.

The Schedule referred to in these Letters Patent and making part of the same.

TO ALL WHOM IT MAY CONCERN:

Be it known that I, WESTEL E. HAWKINS, of Wallingford, in the county of New Haven, and State of Connecticut, have invented a new Improvement in Butter-Dishes; and I do hereby declare the following, when taken in connection with the accompanying drawings, and the letters of reference marked thereon, to be a full, clear, and exact description of the same, and which said drawings constitute part of this specification, and represent, in—

Figure 1, a side view.

Figure 2, the same, turned one-fourth around, and showing the cover opening; and in

Figures 3 and 4, detached views.

This invention relates to an improvement in butter-dishes, such as have the cover pivoted to the bowl, so as to be turned over upon a pivot, and commonly called "revolving butter-dishes," the object being to attach the cover to the bowl, so that while it can be easily detached, it cannot be accidentally detached; and the invention consists in the peculiar manner of forming a lock-joint by making a groove in each of the trunnions, and a projection upon the bearing so as to enter the said grooves, the said projection serving to secure the cover in its position.

In order to the clear understanding of my invention, as well as to enable others to construct the same, I will proceed to a description thereof as illustrated in the accompanying drawings.

A is the bowl, constructed double, and provided with a cover, B, so as to revolve and turn over between the outer and inner bowl, in the usual manner, the trunnions, *a*, of the cover resting in bearings, *b*, on the bowl, the said bearing being shown in fig. 3. Upon the outer end of each of the trunnions is formed a knob or handle, C, for the purpose of turning the cover; and upon the inner end of the neck of the knob, and around the trunnion, I form a groove, *f*, as seen in fig. 4, and cut a notch, *i*, outward; and upon the outer end of the bearing *b*, I form a projection, *d*, as seen in fig. 3, which, when the trunnions are set into the bearing in the proper position, will pass through the opening *i* into the groove *f*, on the neck of the knob, and the position for so entering the groove I find to be best formed at that point where the cover is partially turned, as in fig. 2, and being set on in that position, the projection *d* entering the groove when the cover is turned, the groove permits its free passage upon the projection, and by the said groove and projection securely hold the cover in its bearings, and so that it cannot be removed except when in the position in which it was placed upon its bearings, and there is no liability of its being accidentally removed when in that position.

Having thus fully described my invention, what I claim as new and useful, and desire to secure by Letters Patent, is—

The arrangement of the projection *d* upon the bearings, combined with the groove *f* in the knob around the trunnion, so as to operate in the manner substantially as described.

WESTEL E. HAWKINS.
